CLAIM

The ornamental design for an extruded metal plank for an interlocking field-erectable deck or cover structure, as shown and described.

DESCRIPTION

FIG. 1 is a perspective view from one end, showing an extruded metal plank for an interlocking field-erectable deck or cover structure according to our new design; FIG. 2 is an end elevation view, the opposite end being identical thereto;

FIG. 3 is a right side elevation view thereof; and,

FIG. 4 is a top plan view thereof.
